UNITED STATES PATENT OFFICE.

PROSPER L'ORANGE, OF MANNHEIM-FEUDENHEIM, GERMANY, ASSIGNOR TO THE FIRM: MOTOREN-WERKE MANNHEIM A. G., VORM. BENZ ABT. STATIONÄRER MOTORENBAU, OF MANNHEIM, GERMANY.

AIR AND AUXILIARY PUMP ARRANGEMENT FOR MARINE DIESEL MOTORS.

Application filed May 21, 1924. Serial No. 714,964.

To all whom it may concern:

Be it known that I, PROSPER L'ORANGE, a German citizen, and residing at Mannheim-Feudenheim, Germany, have invented certain new and useful Improvements in an Air and Auxiliary Pump Arrangement for Marine Diesel Motors (for which I have made application for patent in Germany on May 30th, 1923, No. 81590), of which the following is a specification.

As known, the length of marine engines is kept as short as possible to gain a larger hold for the cargo. Thus, generally, the air pumps required for manœuvring and the like are arranged separately from the main engines between engines and ship's side, in which case, however, a separate motor is required for driving said pumps whereby the plant becomes rather expensive. With cross-head engines said drawback is avoided by driving the air pumps as well as the cooling and bilge pumps by radius links from the cross-head in a way known in the art. The provision of such radius links makes the construction and the gearing very complicated.

The present invention provides an improved arrangement by which said drawbacks are effectively overcome and which is represented on the accompanying drawing, in which Figs. 1 and 2 are respectively a sectional side elevation and a sectional plan view of the same.

According to the invention, the cross-head is, in a way known per se, replaced by radius link *c* fulcrumed on each two supports *x* of the engine frame and intervening between the piston rods *z* of each two adjacent engine cylinders *a* and the engine connection rod *b*.

Owing to two adjacent engine cylinders working always on a common radius link, sufficient space is left between the supports *x* for locating the air pump *d* and the cooling and bilge pump *e* vertically above and below a point of the radius link between its fulcrum and its point of connection with the engine connection rod respectively, said pumps being directly driven from said radius link in upward and downward direction respectively.

Thereby, it is possible to locate all the pumps in proximity to the engine middle so that the space required on board by the main engines is fully utilized.

What I claim, is:

In an air and auxiliary pump arrangement for marine Diesel motors: the combination with two adjacent engine cylinders and an engine connection rod; of a common radius link by which said connection rod is adapted to be driven from said cylinders, and an air pump and a cooling and bilge pump respectively located vertically above and below a point on said radius link between its fulcrum and its point of connection with said engine connection rod and adapted to be directly driven from said radius link in upward and downward direction respectively, substantially as and for the purpose set forth.

In testimony whereof I have hereunto set my hand in the presence of two subscribing witnesses.

PROSPER L'ORANGE.
